Specification for Design.

Patented July 9, 1912.

Application filed May 1, 1912. Serial No. 694,574. Term of patent 7 years.

To all whom it may concern:

Be it known that I, SAMUEL N. GOODMAN, a citizen of the United States, residing in Philadelphia, county of Philadelphia, and State of Pennsylvania, have invented a new, original, and ornamental Design for Lace Edging, of which the following is a specification, reference being had to the accompanying drawing, which forms a part thereof.

The drawing is a plan view of a portion of lace edging showing my design.

The design comprises two longitudinal threads connected by a somewhat closely

knitted backing and by pairs of intersecting transverse threads rendered more non-uniform in appearance by not being secured to the backing.

I claim—

The ornamental design for lace edging as shown and described.

In testimony of which invention, I have hereunto set my hand, at Philadelphia, on this 24th day of April, A. D. 1912.

SAMUEL N. GOODMAN.
